UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINES.

Application filed June 18, 1920. Serial No. 389,805.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

This invention relates to typewriting machines, and is herein disclosed as applied to an Underwood continuous billing machine, one form of which is shown in the patent to Wernery and Smith, No. 1,132,055, dated March 16, 1915. In such machines, it is common to use fan-folded webs which are threaded through a carbon-paper carriage, the latter adapted to be reciprocated upon an extension of the typewriter carriage. The fan-folded webs frequently come folded cross-wise, so that they can be handled in the form of bales instead of being wound upon reels or rollers. The transverse folds of such webs frequently interfere with the smooth operation of the machine, especially where the machine is provided with slitters which slit the fan-folded web as it approaches or leaves the carbon-paper carriage. Moreover, these fan-folded webs are frequently made of cheap paper and as economically as possible, with the result that the longitudinal folds are not always located with the accuracy which insures the rapid and accurate working of the machine; especially they are likely to interfere with the clean cutting of the webs by the slitters by being irregularly folded longitudinally.

According to the present invention, this and other troubles in typewriting machines may be overcome by providing ironing or smoothing devices, which are adapted to smooth out any transverse folds which may exist in the fan-folded web, and may iron down the longitudinal folds, thus making the web compact and smooth if passed around the platen uncut. Moreover, these devices make the folds sharp enough to insure that the slitters will slit the webs cleanly, even if the usual perforations along the longitudinal folds of the webs do not exactly follow the line of the fold as sometimes happens.

The smoothing or ironing devices may take the form of channel bars which are attached to the carbon-paper carriage, and which may be broad enough to substantially

smooth out any transverse fold in the web. In order to keep the mechanism light and at the same time render it less liable to be injured by jars, the smoothing devices may be carried upon light, resilient bars attached in any suitable manner to the carbon-paper carriage, and at a considerable distance behind said carriage. It has been found that side gages will work very effectively if mounted upon the channel bars so as to extend their bearing surfaces to engage the webs behind said bars.

Other features and advantages will hereinafter appear.

In the accompanying drawings,

Figure 1 is a perspective view, largely diagrammatic, of an Underwood typewriting machine of the class described, showing my invention applied thereto.

Figure 2 is a sectional side view of the same.

Figure 3 is a rear view of the smoothing devices, showing the gages thereon.

In the usual Underwood continuous billing machine, the displaceable platen 1 forms part of a traveling carriage which also includes a paper table 2 and a cross-bar 3. In such machines, the fan-folded web, including plies 4, 5, and 6, is usually drawn from the rear over the rear cross-bar 7 of an extension 8 of the typewriter carriage, said extension including rails 9, upon which travels a carbon-paper carriage 10, the latter including the usual removable carbon-clip bars or carbon-holders 11, mounted upon the steps 12, carried by the usual detachable base 13. The webs 4, 5, and 6, as they are drawn from the rear over the cross-bar 7, frequently engage slitters or knives 14 mounted upon the ends of the carbon-clip bars 11, said slitters being so positioned that they engage the folds 15 and 16 of the fan-folded web, slitting it so that its separated plies 4, 5, and 6 are threaded between the clip bars 11, and pass forward, being bent down over the cross-bar 3, and carried upon the paper table 2 under the platen and up to the printing line, diagrammatically shown by the type-head 17.

In its normal or writing position, shown in Figures 1 and 2, the platen bears against rear and front feed-rolls 18 and 19. In the usual operation of the machine, when the desired number of lines have been typed upon the outer ply 6 so as to fill up the form

or for any other purpose, the platen 1 is swung to its displaced position, and the web plies 4, 5, and 6 are drawn forward and gaged against the usual leading-edge gage, 5 not shown herein, after which the carbon sheets 20, carried by the clip bars 11, are pulled rearwardly by pushing rearwardly the usual handle 21, which carries rearwardly the carbon-paper carriage, until it reaches 10 a stop 22 of any usual or desired form which arrests the carbon sheets 20, so that their leading ends stand just above the printing line. Then the typist swings the platen 1 back to its typing position, and after severing 15 the leading ends of the webs 4, 5, and 6, by drawing them against the usual knife, not shown, typing proceeds.

According to the present invention, the carbon-paper carriage 10 may carry broad, 20 flat, light, sheet-metal, shallow channel bars 23 and 24, which have their outer flat surfaces against each other, so that if a transverse fold 25 in the fan-folded web comes to the channel bars 23, 24, it is smoothed 25 out in passing between them, owing to the fact that the channel bars 23 and 24 have flat faces 26 opposing each other of sufficient length measured rearwardly to smooth out folds like the fold 25. In order to enable 30 the channel bars 23, 24, to effectively iron out or smooth out the folds in the manner described, they are resiliently held together by a spring 27 at each end, each spring surrounding a headed post 28, which 35 passes through a fairly closely-fitting opening in a thin resilient support or arm 29 fast to the detachable top or base 13, and each post having on its upper end a thumb-screw 30, which is adapted to be screwed 40 down upon the top channel bar 23, thus varying the tension of the spring 27, and thereby varying the force with which the channel bars bear against each other.

In the construction shown, the spring 27 45 forms the support for the channel bars 23, 24, upon the resilient arms 29, with the result that if the channel bars are accidentally hit or caught, the spring 27 and resilient arms or mountings 29 will yield, and thus 50 protect the rest of the mechanism from being wrenched. Each channel bar 23, 24, may extend somewhat outside the adjacent rail 9, and thus provide a long bearing for the extension 31 of an adjacent side gage 32, 55 which extends rearwardly from the channel bar in the form of a flat vertical member. To connect the vertical member with the extension 31, the gage member also includes a flat plate 33 lying close against the rear 60 vertical edges 34 and 35 of the upper and lower channel bars 23 and 24, and then is bent as a closely-fitting U 37, over the edge 34, and then down on the inside of the channel bar to join the extension 31. The wide 65 bearing surface of this character gives suf-

ficient friction to hold the side edge gage 32 in place by the thumb-screw 30, which engages it because the post 28 passes through an opening or slot 39 in the extension 31. Thus, a single thumb-screw 30 at each end 70 holds both the channel bars 23 and 24 in place, and each also holds the adjacent side gage 32 in place.

It will be observed that the channel bars 23 and 24 form admirable ironing devices 75 for ironing down the longitudinal folds 15 and 16 of the fan-folded web. They also serve to smooth down not only folds like the fold 25, but also folds 40, which usually alternate with folds like fold 25 in fan-folded webs as usually sent to market. The channel bars 23, 24, may be exceedingly light and yet will be found very effective if their engaged faces are in the neighborhood of $1\frac{1}{2}$ long. Where they are this 85 size, the spring 27 need not be of sufficient strength to create an undue friction upon the web, with the result that the presence of the smoothing device is practically unnoticed in the usual operation of the machine. 90 The supporting arms 29 may be held in place by screws 41, which are threaded through the detachable base 13 from the bottom, and an arm 29 may underlie the step base 12 on each side of the detachable 95 base 13.

It is found that by using the thin flat plates 14 of metal as extensions of the clip bars for the severing devices, the ironing down of the longitudinal folds by the channel plates will ensure clean severing of the plies 4, 5, and 6, even if the usual perforations along the folds 15 and 16 do not run true, thus avoiding the irregular cutting which might otherwise result.

Variations may be resorted to within the scope of the invention, and portions of the improvements may be used without others.

Having thus described my invention, I claim:

1. In a typewriting machine, the combination with a traveling carriage and a displaceable platen, of a carbon-paper-carriage reciprocable on the traveling carriage, and through which a fan-folded web may be 11 threaded, slitters for said web, and a smoothing device for smoothing the web as it approaches the slitters.

2. In a typewriting machine, the combination with a traveling carriage and a displaceable platen, of a carbon-paper-carriage reciprocable on the traveling carriage, and through which a fan-folded web may be 12 threaded, slitters for said web, a pair of plates behind the slitters, means for resiliently holding said plates together so that they form a smoothing device for the web, and gages at the plates to side-gage the web.

3. In a typewriting machine, the combination with a traveling carriage and a dis-

placeable platen, of a carbon-paper-carriage reciprocable on the traveling carriage, carbon-clip-bars upon said carbon-paper-carriage through which a fan-folded web may be threaded, slitters for the web upon said clip-bars, and a device upon the carbon-paper-carriage for smoothing the web as it approaches the slitters.

4. In a typewriting machine, the combination with a traveling carriage and a displaceable platen, of a carbon-paper-carriage reciprocable on the traveling carriage, carbon-clip-bars upon said carbon-paper-carriage through which a fan-folded web may be threaded, slitters for the web upon said clip-bars, and a pair of plates carried by the carbon-paper-carriage resiliently bearing upon each other to smooth the web.

5. In a typewriting machine, the combination with a traveling carriage and a displaceable platen, of a carbon-paper-carriage reciprocable on the traveling carriage, carbon-clip-bars upon said carbon-paper-carriage through which a fan-folded web may be threaded, slitters for the web upon said clip-bars, and means for pressing down each fold of the web behind its slitter to enable the slitter to cut it smoothly.

6. In a typewriting machine, the combination with a traveling carriage and a displaceable platen, of a carbon-paper-carriage reciprocable on the traveling carriage, and through which a fan-folded web may be threaded, slitters for said web, a pair of plates behind the slitters for smoothing the web, a spring for adjustably holding said plates together, and a resilient mounting for said plates upon the carbon-paper-carriage.

7. In a typewriting machine, the combination with a traveling carriage and a displaceable platen, of a carbon-paper-carriage reciprocable on the traveling carriage, and through which a fan-folded web may be threaded, slitters for said web, a plate carried by the carbon-paper-carriage behind the slitters, a second plate above the first, an adjustable gage carried upon the plates, a post, a thumb-screw adapted to be turned down upon the post to bind the plates and gage together, and a spring by which the post bears upon one of the plates to resiliently vary the pressure of the plates.

8. In a typewriting machine, the combination with a traveling carriage and a displaceable platen, of a carbon-paper-carriage reciprocable on the traveling carriage, and through which a fan-folded web may be threaded, slitters for said web, means behind each slitter for ironing down the web-fold as it approaches its slitter, and a side gage at said means.

9. In a typewriting machine, the combination with a traveling carriage and a displaceable platen, of a carbon-paper-carriage reciprocable on the traveling carriage, and

through which a fan-folded web may be threaded, slitters for said web, means behind each slitter for ironing down the web-fold as it approaches its slitter, an adjustable side gage for the web at said means, and a resilient device for adjustably varying the tension of the ironing means.

10. In a typewriting machine, the combination with a traveling carriage and a displaceable platen, of a carbon-paper-carriage reciprocable on the traveling carriage, and through which a fan-folded web may be threaded, slitters for said web, a broad light channel plate extending across the machine behind the slitters, a second broad light channel plate lying against the first, and resilient devices holding the plates together to enable them to iron out the web in being drawn through them.

11. In a typewriting machine, the combination with a traveling carriage and a displaceable platen, of a carbon-paper-carriage reciprocable on the traveling carriage, and through which a fan-folded web may be threaded, slitters for said web, a broad light channel plate extending across the machine behind the slitters, a second broad light channel plate lying against the first, resilient devices holding the plates together to enable them to iron out the web in being drawn through them, and an adjustable gage for the web at each end of the plates.

12. In a typewriting machine, the combination with a traveling carriage and a displaceable platen, of a carbon-paper-carriage reciprocable on the traveling carriage, and through which a fan-folded web may be threaded, slitters for said web, a broad light channel plate extending across the machine behind the slitters, a second broad light channel plate lying against the first, an adjustable side gage for each side of the web supported on one of the plates, and a single releasable device for adjusting each gage and the bearing of the plates upon each other.

13. In a typewriting machine, the combination with a traveling carriage and a displaceable platen, of a carbon-paper-carriage reciprocable on the traveling carriage, and through which a fan-folded web may be threaded, slitters for said web, a broad light channel plate extending across the machine behind the slitters, a second broad light channel plate lying against the first, an adjustable side gage for each side of the web supported on one of the plates, and means for resiliently supporting said plates on the carbon-paper-carriage.

14. In a typewriting machine, the combination with a traveling carriage and a displaceable platen, of a carbon-paper-carriage reciprocable on the traveling carriage, and through which a fan-folded web may be threaded, slitters for said web, a broad light channel plate extending across the machine

behind the slitters, a second broad light channel plate lying against the first, resilient devices holding the plates together to enable them to iron out the web in being drawn through them, a gage for each side of the web extending behind the plates, an extension of each gage lying close to the adjacent plate and fitting into its channel, and means for adjustably holding the gages in

10 place.

15. In a typewriting machine, the combination with a traveling carriage and a displaceable platen, of a carbon-paper-carriage reciprocable on the traveling carriage, and through which a fan-folded web may be threaded, slitters for said web, a broad light channel plate extending across the machine behind the slitters, a second broad light channel plate lying against the first, a support for each end of the plates extending from the carbon-paper-carriage, a post extending through both plates and each support, and comprising a head, a spring for each post, and a thumb-screw adapted to be screwed down on each post to bind the plates resiliently together by the spring.

16. In a typewriting machine, the combination with a traveling carriage and a displaceable platen, of a carbon-paper-carriage reciprocable on the traveling carriage, and through which a fan-folded web may be threaded, slitters for said web, a broad light channel plate extending across the machine behind the slitters, a second broad light channel plate lying against the first, a support for each end of the plates extending from the carbon-paper-carriage, a post extending through both plates and each support, and comprising a head, a spring for each post, a thumb-screw adapted to be screwed down on each post to bind the plates resiliently together by the spring, and side gages supported on said plates and adjustably fastened by said screws.

45 17. In a typewriting machine, the combination with a traveling carriage and a displaceable platen, of a carbon-paper-carriage

reciprocable on the traveling carriage, and through which a fan-folded web may be threaded, slitters for said web, a pair of light channel bars behind the slitters and adapted to iron out webs, a pair of side gages comprising extensions fitting into the channels for adjustably supporting them, and means for resiliently holding the channel bars together.

18. In a typewriting machine, the combination with a traveling carriage and a displaceable platen, of a carbon-paper-carriage reciprocable on the traveling carriage, and through which a fan-folded web may be threaded, slitters for said web, a pair of light channel bars behind the slitters and adapted to iron out webs, a pair of side gages comprising extensions fitting into the channels for adjustably supporting them, means for resiliently holding the channel bars together, and resilient extensions extending rearwardly from the carbon-paper-carriage to support the bars.

19. In a typewriting machine, in combination, a traveling carriage, a platen, a reciprocable carbon-paper carriage at the rear of the platen and through which a fan-folded web may be threaded, slitters for said web, and a device for flattening and creasing the web for slitting as it approaches the slitters.

20. In a typewriting machine, in combination, a traveling carriage, a platen, a reciprocable carbon-paper carriage at the rear of the platen and through which a fan-folded web may be threaded, slitters for said web, a pair of pressing members behind the slitters and between which the web passes, and means for resiliently holding such members together so as to flatten and crease the folds of the web for slitting as it approaches the slitters.
